Application June 15, 1931. Serial No. 544,345

8 Claims. (Cl. 197—74)

This invention relates to improvements in type-writing machines, and particularly to devices for shifting the platen and the type bars relatively to each other for changing from upper to lower case type, and vice versa.

The principal object of this invention is the provision of simple and inexpensive means for shifting the platen and type bars relatively to each other for changing case, said means being so arranged that the load on the actuating parts is reduced to a minimum, resulting in substantially noiseless operation.

Another object of the invention is to mount the shiftable part in a case shift mechanism on the free ends of a plurality of springs, which tend to resiliently move it toward one case position and guide its movement toward and from the other case position.

A still further object of the invention is the provision of resilient guiding members on a fixed part, each of which is arranged between a pair of fixed stops on the movable part and which is engaged by one or the other of said stops before the shiftable part reaches the limit of its movement and serves to slow up its movement and eliminate the noise normally caused by the force of impact.

Still another object of the invention is the provision of simple and readily accessible means for adjusting the type basket to bring the concave types into proper engagement with the curved surface of a cylindrical platen.

Another object of the invention is the provision of means for shortening the path of movement of the type bar when shifted to write upper case characters so that they will be struck with greater force than the lower case characters which have less printing surface area.

To these and other ends, the invention consists in the construction and arrangement of parts that will appear from the following description when read in conjunction with the accompanying drawings, the novel features being pointed out in the claims at the end of the specification.

In the drawings:

Fig. 1 is a transverse section of a typewriting machine illustrating one possible embodiment of the invention;

Fig. 2 is a similar view showing the parts in the other case position;

Fig. 3 is a side elevation of a leaf spring for supporting and lifting the shiftable part;

Fig. 4 is a plan view of the same;

Fig. 5 is a fragmentary view illustrating certain

of the shifting devices at the opposite side of the machine in the Fig. 2 position;

Fig. 6 is an enlarged fragmentary detail view of the type;

Fig. 7 is a fragmentary transverse section of a typewriting machine illustrating an arrangement for varying the force of the type blow on the platen when the type basket is shifted from one case position to another;

Fig. 8 is a similar view showing the type basket in another position;

Fig. 9 is a view similar to Fig. 6 showing a modified type arrangement for use with the construction shown in Figs. 7 and 8, and Fig. 10 is a fragmentary detail view of a toggle lever and its actuator shown in rear elevation.

Although the invention as illustrated is embodied in a power driven typewriting machine, it will be understood that its use is not limited to such machines, but is applicable to various machines in which the type bars are shiftable relatively to the platen for changing case. This machine comprises a frame 1 in which a type basket 2 is movably mounted. A plurality of type bars, one of which is shown at 3, are pivotally mounted in the type basket for cooperation with the printing point on the platen. Each of the type bars has two types 5, one for lower and the other for upper case printing. With the parts in the normal position shown in Fig. 1, the lower one of the types 5 engages the platen for printing when the type bar is actuated. When, however, the type basket is shifted to the Fig. 2 position, the other type 5 engages the platen for printing.

The type basket 2 is mounted on the free front ends of a plurality of leaf springs 6 and 7. It will be understood that two of each of said springs are employed, one at each side of the type basket. The springs 6 are secured at their rear ends to brackets 8 projecting from the frame and extend upwardly and forwardly therefrom and at their free ends are secured to lugs 9 projecting rearwardly from the type basket. The springs 7 are secured at their rear ends to brackets 10 projecting from the frame and extend upwardly and forwardly therefrom in substantially parallel relation to the springs 6, and at their forward ends are secured to the type basket. By this arrangement, the type basket is resiliently supported and guided in its case shift movements on the free ends of the springs 6 and 7.

Power actuated key controlled means are provided for shifting the type basket. Said means

90

95

100

105

110

in the embodiment illustrated comprises two toggles so arranged that one or the other is in its straightened position when the type basket is shifted to one or the other of its printing positions. One of said toggles comprises the link 12 pivoted at one end to a bracket 13 projecting rearwardly from the type basket. The other end of the link 12 is pivoted to the arm 14 of a bell crank lever fixed on one end of a rock shaft 15 mounted on a fixed part and extending to the other side of the type basket. The other arm 16 of the bell crank is connected with a toggle lever 17 by means of a link 18. By this arrangement, the link 12 and arm 14 constitute in effect a toggle, moved to its straight position when the type basket is in its upper or normal position, as seen in Fig. 1. This toggle not only serves to raise the type basket, but also to slow up and limit its upward movement. It will be noted that when the parts are in this position, the pivotal points of the link 12 are in substantial alinement with the axis 15 of the bell crank.

The toggle lever 17 and link 18 constitute in effect a second toggle movable from the broken position shown in Fig. 1 to the straightened position shown in Fig. 2, in which the pivotal points of the link 18 are in substantial alinement with the pivot of the lever 17 when the type basket is shifted to its lower position, and this toggle serves to slow up and limit the downward movement of the type basket.

Power driven key controlled means are provided for actuating said toggles to shift the type basket. Said means comprises a power driven roller 20 and a bell crank pivoted at 21 adjacent thereto on the frame. One arm 22 of the bell crank projects rearwardly from its pivot and has its free end connected with an arm 23 of a three-armed lever by means of a link 24. Said three-armed lever is pivoted on the frame and has an arm 25 to which a rearwardly extending interponent 26 is pivoted. The interponent 26 lies closely adjacent the lever 17 and at its end is provided with oppositely projecting fingers or lugs 27 and 28 adapted to engage one or the other of a pair of cooperating lugs or projections 29 and 30 projecting laterally from the lever 17, and arranged on diametrically opposite sides of its pivot 17'. The free ends of the lugs or pins 29 and 30 are connected by means of a plate 26', as shown in Fig. 10, which serves to retain the interponent therebetween. The other arm 31 of the bell crank projects downwardly from the pivot 21 and has a cam 32 pivotally mounted thereon adjacent its lower end and arranged adjacent the surface of the power driven roller 20. The cam 32 has a pair of lugs 33 and 34 projecting laterally therefrom on opposite sides of its pivot, one or the other of which is engaged by a spring-pressed arm 35 pivoted on the arm 31 and which tends to turn the cam into engagement with the roller 20. The cam also has a pair of laterally projecting stops 36 and 37 arranged on opposite sides of and at different distances from its pivot and adapted to cooperate with a stop provided on the lower end of a lever 38 also pivoted on the arm 31. The upper end of the lever 38 is provided with a laterally projecting lug which is engaged in a slot in the end of an arm 41 depending from a key lever 42 having a key 43 by which it may be manually operated. The key lever is pivoted on a fixed part and has a rearwardly extending arm 44 which is slotted at its end for engagement with an eccentrically adjustable stud 45 projecting laterally from the

interponent 26 at a point adjacent to but in rear of the arm 25. This adjustment permits accurate timing of the release lever and interponent 26.

The type basket is shifted to upper case position when the key is depressed and returned to lower case position when the key is released, and it is therefore customary to hold the key depressed while writing upper case characters. In the illustrated embodiment, when the key is depressed, the lower end of the lever 41 swings forwardly and moves the stop or lug 46 on arm 31 from the path of the stop 36 and into the path of the stop 37 and permits the cam to move into engagement with the power roller under the action of the arm 35. By the engagement of its arm 44 with the interponent 26, the rear end of the interponent is raised from the position shown in Fig. 1 to that shown in Fig. 2 when the key is depressed. If the key is held depressed, as shown in Fig. 2, the cam 32 is turned through one-half a revolution until its stop 37 moves into engagement with the stop 46 on the arm 38. During this movement of the cam, the arm 22 is depressed and swings the arm 25 forwardly and with it the interponent 26, which by its position engages the lug 30 with its finger 28 and swings the arm or lever 17 about its pivot 17', which in turn swings the arm 16 of the bell crank forwardly to straighten the toggle 17, 18, and moves the arm 14 rearwardly to break the toggle 12, 14 and swing the type basket downwardly against the tension of the spring arms 6 and 7. The parts come to rest while the key lever is held depressed in the position shown in Fig. 2. When the key lever is released, the cam 32 is again moved into engagement with power driven roller and the interponent returned to the Fig. 1 position. The cam makes another half rotation, during which the interponent 26 is again actuated and engages the lug 29 on the lever 17 and swings the lever to break its toggle and at the same time swings the bell crank to again straighten the toggle 12, 14 against the tension of the springs 6 and 7 to return the type basket to normal lower case position.

A spring 51 connects the arm 52 of the three-armed lever with the frame of the machine and tends to resiliently retain said lever in its normal position and to return it and with it the interponent 26 after each actuation. A stop 53 adjustably mounted on the frame of the machine is normally engaged by the arm 52 and limits the movement of the three-armed lever under the action of the spring. The stop 53 is in the form of a headed bolt adjustably secured in the frame of the machine. A stop 54 is mounted on the rear end of a resilient bent arm 55 secured to the frame at one end and having its free end on which the stop is mounted free from the frame. The stop 54 is engaged by a stop 56 on the lever 17 when its toggle is straightened, and the resiliency of its arm serves to avoid the noise which might otherwise be caused by such engagement.

As stated above, the bell crank 14, 16 is mounted on a rock shaft 15 which extends to the right hand side of the type basket. Means operatively connected with said rock shaft are provided for shifting the right side of the basket simultaneously with the left side so that all parts of the type basket move simultaneously in substantially parallel lines. To this end, a lever 61 is fixedly mounted on the right hand end of the shaft 15,

see Fig. 5, to which one end of a link 62 corresponding to the link 12 is pivoted at 63. The other end of the link 62 is pivoted to a bracket 64 secured to the right side of the type basket 5 and corresponding to the bracket 13 at the left hand side of the basket. The lever 61 has an arm 65 projecting rearwardly from the pivot 63, as seen in Fig. 5, which is adapted to engage the bracket 64 when the toggle, comprising the link 10 62 and the lever 61, is moved to the straight position in which the pivots of the link 62 are substantially aligned with the axis of the rock shaft 15, and the type basket is in its elevated or lower case position corresponding to the position 15 shown from the left in Fig. 1. A spring 66 connects a forwardly projecting arm 67 on the lever 61 with a fixed part and passes over the axis 15 when the lever 61 swings to shift the type basket and resiliently tends to retain the basket 20 in either shifted position.

Means are also provided for guiding the type basket in its shift movements and cooperating with the toggles previously described for resiliently slowing up or stopping its movement toward either shift position. To this end, a resilient arm 71 is secured to a bracket on the frame of the machine and extends forwardly and upwardly therefrom in a plane substantially perpendicular to the path in which the type basket 30 moves. It will be understood that two of the arms 71 are provided, one at each side of the type basket, although only one of them is shown in the drawings. At its forward end, the arm 71 is provided with an opening in which a rod or 35 bolt 72 is arranged. The bolt 72 is mounted in a bracket 73 on the type basket frame and depends downwardly and forwardly therefrom in a plane substantially parallel with the path in which the type basket moves.

40 Fixedly mounted on the lower end of the bolt 72 is a stop 74 which normally engages the finger 71 when the type basket is in the normal lower case position shown in Fig. 1. If desired, a sound deadening cushion 75 of fibrous material, such as felt, may be arranged on the stop to engage the arm. In order that the stop may be arranged in position to engage the arm 71 at the time when the basket approaches the limit of its upward movement and the lower type is 45 properly positioned with respect to the printing point on the platen, means are provided for adjusting the bolt axially and with it the stop 74. To this end, the bolt is threaded in a tapped opening in the bracket 73 and adapted to be 50 turned in one direction or the other by means of a suitable tool to move it axially in the bracket. A lock nut 76 is threaded on the upper end of the bolt into engagement with the bracket 73 to secure the bolt in adjusted position. A second stop 77 in the form of a nut is threaded on the bolt to be adjustable thereon between the stop 74 and the bracket 73. The stop 77 is locked in 55 adjusted position by means of a lock nut 78 threaded on the bolt in engagement therewith. The stop 77 is so adjusted on the bolt that it, or a sound deadening cushion arranged thereon, moves into engagement with the arm 71 as the type basket approaches the limit of its downward movement and when the upper type 5 is in position to engage the printing point on the platen. It will be noted that by this arrangement, the stops 74 and 77 can be adjusted to so position the type basket in either case position that the types 60 are properly aligned with the printing point on

the platen, even though the bearings of the parts of the toggles become worn.

In machines of this kind having a cylindrical platen, the types are made concave to correspond to the curvature of the platen with which they co-operate. It is therefore essential that the types strike the platen in such position that the radius of curvature of the types is in alignment with the radius of curvature of the surface of the platen, in order that a full clear type impression be made on the work sheet. Means are therefore provided for adjusting the type basket relatively to the printing point so that the concave types may fully register with the convex surface of the platen throughout their entire areas. To this end, the brackets 13 and 64 in which the links 12 and 62 are pivoted have bearings on trunnions 81 provided therefor on the type basket. Each of the brackets projects both above and below the trunnion and is secured to the type basket at its ends by means of headed screws 82 and 83 arranged in openings in the type basket frame and projecting rearwardly therefrom on opposite sides of the trunnion 81. The bracket is provided with openings adjacent its upper and lower ends, whereby it is arranged on the screws 82 and 83 and its bearing 81 and secured in such position by means of nuts threaded on the rear ends of the screws. Guide members 84 and 85 project rearwardly from the type 105 basket frame adjacent the trunnion 81 and engage the bracket to prevent lateral play between it and the basket. By this arrangement, the type basket is free from the ends of the bracket and by turning one of the screws in one direction 110 and the other in the reverse direction, the relation of the type basket to the bracket 13 and the center of curvature of the platen may be varied. Since this adjustment is very small, the springs or arms 6 and 7 readily accommodate 115 themselves to it. It will be noted that when the parts are in the normal Fig. 1 position, the pivots of the link 12 are in substantial alignment with the axis of the bell crank 14 so that its distance from the axis is substantially fixed. This adjustment of the bracket, however, also affects its upper case position or the position it occupies when the toggle 17, 18 is straight. Means are therefore provided for adjusting the lever 17 on its axis to vary the shift movement of the basket 120 so that the upper case types properly engage the platen when the basket is shifted to the upper case position shown in Fig. 2. To this end, the pivot 17' for the toggle lever 17 may be eccentrically mounted on the frame, as shown, to permit of a limited adjustment of the axial center of the toggle lever whereby the distance through which the basket is shifted may be varied.

Referring now particularly to the construction shown in Figs. 7, 8 and 9, the type basket 101 135 is mounted on the free ends of resilient arms 102 and 103 projecting forwardly from brackets 104 and 105 projecting upwardly from the frame member 1. The arms 102 and 103 and brackets 104 and 105 are so constructed and arranged that 140 when the type basket is in the normal or lower case position, the arms 102 and 103 project upwardly and forwardly from the brackets in substantially parallel planes, but when the basket is shifted from the Fig. 7 to the Fig. 8 position against the tension of the resiliency of the arms 102 and 103, said arms are curved to the form substantially shown in said Fig. 8. The arms 103 are longer than the arms 102 and swing 145 about an axis at a greater distance to the rear 150

of the type basket than the axis of the arms 102. In the arrangement illustrated, the force which moves the type basket operates in a direction tangent to the curved paths described 5 by the forward ends of the resilient arms. In the device illustrated in Figs. 1 to 6 of the drawings, the type basket moves through this point of tangency when shifted, and since the path of movement is short and the effect of the curvature of its path is split or bisected, so to speak, the parts of the type basket in shifted position occupy substantially the same relative positions as when in the normal position, except that they are farther from the printing point on the platen. 10 In the construction shown in Figs. 7 and 8, the type basket normally occupies a position in which the shifting force is tangent to its path of movement, and hence its path of movement is substantially a component of the movement 15 of those parts which are secured to the free ends of the arms 102 and 103. By comparing Figs. 7 and 8 of the drawings, it will be noted that this component movement is downwardly and rearwardly in a curved path from its normal 20 or lower case position, but owing to the shorter radius of movement of its lower end, said lower end tends to move rearwardly slightly more rapidly than other parts of the basket, so that it comes to rest in upper case position as shown 25 in Fig. 8, when shifted from the lower case position shown in Fig. 7. The result of this movement is to bring the normal inoperative position of the type bars nearer to the printing point, so that when actuated they swing through a 30 shorter arc and strike the platen or the work sheet thereon with a heavier blow, or before it has an opportunity to slow up at the end of its movement. By varying the relative lengths of the resilient arms 102 and 103, the arc through 35 which the type bar swings to engage the platen 40 may be varied within certain limits.

By a comparison of Figs. 7 and 8 it will be noted that the angular position of the type bar relative to the printing point on the platen 45 changes when the type basket is shifted, with the result that with a type bar such as shown in Fig. 6 and having the faces of its type arranged in substantially the same plane, one of 50 the types would strike the platen on its edge and fail to make a clear impression on the work sheet when the type basket was in one of its shifted positions. In Fig. 9, a type bar is shown in which one of the types 106, the upper case in this instance, is inclined relatively to the type bar or other type so that its face fully 55 engages the surface of the platen when moved to the printing point.

When the basket is shifted to the upper case 60 position from the Fig. 7 position to that shown in Fig. 8, or to the dotted line position, the parts of the basket move along the arcs indicated in broken lines, which causes the basket to swing rearwardly, but since the arm 102 is shorter than the arm 103, its forward end describes an arc of 65 greater curvature than the forward end of the arm 103 which causes the lower end of the basket to swing rearwardly to a greater extent than the part to which the forward end of the arm 103 is secured. This causes the upper end of 70 the basket to swing less rapidly, and parts of the basket when in one position are slightly inclined relatively to their positions when in the other shifted position; as a result, the types move 75 toward the platen and if the faces of the types on the type bar are in parallel planes or the

same plane, one or the other would not make a perfect impression, and for this reason the face of one of the types on the type bar is inclined relatively to the face of the other type.

In a construction such as shown in Figs. 1 to 80 5, the parts of the basket are arranged in substantially parallel planes in either shifted position, and the faces of the types are in the same plane or parallel planes. Due to the normal curvature of the arms 6 and 7, when the basket 85 is shifted from the full line to the dotted line position shown in Fig. 1, it moves forwardly during the first half of its movement and an equal distance rearwardly during the second half of its movement, so that it comes to rest in 90 either position with its parts arranged in planes substantially parallel with the planes in which said parts are arranged when the basket is in its other position and at the same distance from the platen. The means for moving the basket 95 and controlling the extent of movement may be the same for the modification shown in Figs. 7 and 8 as for that shown in Figs. 1 to 5.

Although only two embodiments of the invention are shown and described herein, it will 100 be understood that this application is intended to cover such other changes or modifications as come within the spirit of the invention or scope of the following claims.

We claim:

1. In a typewriting machine, the combination of a frame, a platen, a type basket, a type bar movably mounted in said type basket, upper and lower case types on said type bar, means for shiftably supporting the type basket on the 110 frame, a bell crank mounted in the frame, means operatively connecting one arm of said bell crank with the type basket, a lever pivoted on the frame, a link pivotally connected at one end to said lever and at its other end to the other arm 115 of said bell crank and having its pivots in substantial alinement with the pivot of the lever when the type basket is in one shift position and out of such alinement when the basket is in another shift position, and key controlled means 120 for swinging said lever in one direction or the other to shift the type basket from one case position to another.

2. In a typewriting machine, the combination of a frame, a platen, a type basket, a type bar 125 movably mounted in said type basket, upper and lower case types on said type bar, means for shiftably supporting the type basket on the frame, a bell crank mounted in the frame, means operatively connecting one arm of said bell crank 130 with the type basket, a lever pivoted on the frame, a resilient stop for limiting the movement of said lever in one direction, a link pivoted at its ends to the free end of said lever and the other arm of said bell crank and having its pivots in substantial alinement with the pivot of 135 said lever when the lever engages said resilient stop, and key controlled means for swinging said lever in one direction or the other to shift the type basket from one case position to another. 140

3. In a typewriting machine, the combination of a frame, a platen, a type basket, a type bar movably mounted in said type basket, upper and lower case types on said type bar, means for shiftably supporting the type basket on the frame, a bell crank mounted in the frame, means operatively connecting one arm of said bell crank 145 with the type basket, a lever pivoted on the frame, a link pivoted at its ends to the free end of said lever and the other arm of said bell crank, key 150

- controlled means for swinging said lever in one direction or the other to move the pivots of said link to and from a position of substantial alinement with the pivot of said lever to shift the basket to and from one case position, and means for adjusting the lever to vary the extent of movement of the basket required for shifting it to and from said case position. 80
4. In a typewriting machine, the combination of a frame, a platen, a type basket, a type bar mounted in said type basket and movable into engagement with the platen, upper and lower case types on said type bar, arms on which said type basket is carried, said arms being of unequal lengths so that they swing the type basket in a curved path to shorten the path of movement of the type bar when the basket is moved to one case position, and means for moving the type basket to shift it from one case position to another. 85
5. In a typewriting machine, the combination of a frame, a platen, a type basket, a type bar mounted in said type basket and movable into engagement with the platen, upper and lower case types on said type bar, resilient arms on which said type basket is carried normally tending to resiliently move the type basket toward lower case position and arranged in substantially parallel planes and those in one plane being shorter than those in another plane so that they swing the type basket to shorten the path of movement of the type bar when flexed by the movement of the type basket to upper case position, and means for shifting the basket. 90
6. In a typewriting machine, the combination of a frame, a cylindrical platen, a type basket, a type bar mounted in said type basket and movable into engagement with the platen, upper and lower case types on said type bar, arms of unequal length on which said type basket is carried and operative to swing the type basket to shorten the path of movement of the type bar when the type basket is moved to one case position, the faces of said types being relatively inclined to fully engage the printing point on the platen in either case position, and means for shifting the basket. 95
7. In a typewriting machine, the combination of a frame, a platen, a type basket, a type bar movably mounted in said type basket, upper and lower case types on said type bar, means for shiftably supporting the type basket on the frame, means for shifting the type basket to and from either case position, said means comprising a bell crank lever, a link connecting one arm of said bell crank with the type basket and movable to and from alinement therewith, an actuating lever pivoted on the frame, a second link connecting said actuating lever with the other arm of said bell crank and movable to and from pivotal alinement with the actuating lever, and key controlled means for moving the actuating lever out of alinement with said second link to swing the bell crank to move its arm into alinement with the first mentioned link. 100
8. In a typewriting machine, the combination of a frame, a cylindrical platen, a type basket, a type on said type bar having a curved face corresponding to the curvature of the platen, a plurality of resilient arms on which the type basket is carried, a bracket to which said type basket is secured, and means for adjusting the type basket on said bracket against the resiliency of said arms to move the type relatively to the platen when in the printing position so that its radius of curvature is in substantial radial alinement with the radius of the platen. 105
